Primary Examiner — Paula Allen Greene

(57) **CLAIM**

The ornamental design for a USB conference microphone, as shown and described.

DESCRIPTION

FIG. 1 is a front, right and top perspective view of a USB conference microphone showing my new design;
FIG. 2 is a rear, left and bottom perspective view thereof;
FIG. 3 is a front, left and bottom perspective view thereof;
FIG. 4 is a front view thereof;
FIG. 5 is a rear view thereof;
FIG. 6 is a left view thereof;
FIG. 7 is a right view thereof;
FIG. 8 is a top view thereof; and,
FIG. 9 is a bottom view thereof.

(Continued)

The broken lines in the drawings illustrate portions of the USB conference microphone, which form no part of the claimed design.
